(57) **CLAIM**

The ornamental design for a personal digital assistant, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of an embodiment of a personal digital assistant showing my new design;

FIG. 2 is a front elevational view thereof;

FIG. 3 is a perspective view of another embodiment of a personal digital assistant; and,

FIG. 4 is a front elevational view thereof.

The claimed portion shown in FIGS. 1–2 and FIGS. 3–4 is part of a touch panel or a computer generated animated image for a display panel or a screen.

The broken line showing of the drawing disclosure is for illustrative purposes only and forms no part of the claimed design.
